UNITED STATES PATENT OFFICE.

GEORGE L. BROWNELL, OF WORCESTER, MASSACHUSETTS.

TENSION DEVICE.

1,243,036.

Specification of Letters Patent. Patented Oct. 16, 1917.

Application filed February 15, 1915. Serial No. 8,147.

To all whom it may concern:

Be it known that I, GEORGE L. BROWNELL, a citizen of the United States, residing at Worcester, in the county of Worcester and 5 Commonwealth of Massachusetts, have invented a new and useful Improvement in Tension Devices, of which the following, together with the accompanying drawings, is a specification.

10 My present invention relates to a tension device especially adapted for use in connection with a twisting machine in which a multiplicity of threads are twisted into a single cord, the threads forming each of 15 the cords being wound upon a common beam. The objects of my invention are to apply a uniform tension to each of the individual threads forming the twisted cord so that any tensile strain applied to the cord 20 will be uniformly resisted by all its component threads, and to apply a uniform tension to the twisted cord as it is laid upon the winding spools of the machine.

A uniform tension of the cord and also of 25 the individual threads composing it is desirous in all cases, but in many twisted cords it becomes a necessity as, for example, in the case of twisted threads employed in leather sewing machines.

30 I accomplish the above objects, among others, by means of the mechanism herein-after described, the novel features being pointed out in the annexed claims.

Referring to the accompanying drawings, 35 Figure 1 is a front elevation of a twisting machine for twisting a multiplicity of threads into a single cord, the threads to be twisted being arranged in groups upon a single beam.

40 Figure 2 is an end view of that portion of the framework of the machine upon which the beams are supported.

Fig. 3 is a plan view upon a smaller scale of the two thread beams, and

45 Fig. 4 is a diagrammatic view illustrating the operation of the tension device at different diameters of the beam.

Similar reference characters refer to similar parts in the different figures.

50 Referring to the accompanying drawings, 1 denotes the framework of a twisting machine, a portion of which is shown in front elevation in Fig. 1. Supported in the framework 1 in vertical bearings are a series of 55 twisting heads 2 arranged in rows upon the

opposite sides of the machine, each of the twisting heads comprising a winding spool 3. The construction and operation of the twisting heads form no part of my present invention and are, therefore, not described 60 in detail as they are of the common form by which a multiplicity of threads are twisted and laid upon the winding spools by means of revolving fliers.

The threads to be twisted are arranged in 65 groups and wound upon a beam 4 supported in vertical brackets 5 mounted upon the framework of the machine. Each group of threads to be twisted in a single cord are taken from the beam and carried around 70 pins 6 held in a triangular framework 6^a and also around pins 7 in the framework of the machine. From the pins 7 the assembled threads are carried to the twisting heads 2. An initial tension is imparted to each 75 group of threads as it is taken from the beam 4 by means of a weight 8 which rests upon the threads wound upon the beam, thereby imparting a sufficient resistance to the rotation of the beam 4 to give the desired tension to the individual threads as 80 they are unwound from the beam.

As the threads are unwound, the diameter of the beam 4 is constantly decreasing and the resistance to the rotation of the beam 85 must also decrease in order to preserve a uniform tension upon the threads. I accomplish this result by continually decreasing the effective pressure of the weight 8 upon the threads as the diameter of the beam 90 decreases, and I accomplish this by carrying the weight 8 upon the free ends of arms 9 which are pivotally held upon a rod 10. The rod 10 is journaled in bearings 11 which are swiveled upon the ends of adjusting 95 screws 12, 12 held in screw threaded holes in arms 13, supported upon the brackets 5, which permit the rod 10 to be raised or lowered. The diameter of a filled beam is represented in Fig. 2 by the broken line 14, 100 and the diameter of a substantially emptied beam by the broken line 15. The maximum effective pressure of the weight 8 upon the threads of the beam will be exerted when the rod 10 is at the proper elevation to hold 105 the arms 9 in a horizontal plane, as represented in Fig. 2. As the diameter of the beam diminishes and gradually approaches the diameter indicated by the broken line 15, the weight 8 will fall and its effective pres- 110

sure become gradually reduced, being the smallest when it has assumed the position indicated by the broken line 16, Fig. 2.

When the tension device is applied to a filled beam, the rod 10 is adjusted vertically to produce the requisite pressure of the weight 8 upon the threads. If the pressure of the weight 8 is found too great, the rod 10 is raised in the arms 13 to bring the arm 9 at 10 an oblique angle to a horizontal plane, thereby reducing the effective pressure of the weight 8 upon the threads. The under side 17 of the weight 8 is curved so that, as the weight 8 descends, the curved surface will 15 be substantially tangential in any position to the cylindrical contour of the beam, and the surface of the weight 8 in contact with the threads will remain constant as indicated by the diagram shown in Fig. 4, which represents the weight 8 in five different positions, *a*, *b*, *c*, *d* and *e*, and having the surface 17 so curved that its contact with the threads of the beam will, in each position, form the same angle with the radial line 18, 20 25 of the beam. The radial line 18, 18 forms a right angle to the line 19 which joins the point of contact 20 of the weight 8 with the threads of a full beam and the axis 21 of the swinging arm 9. As the weight descends 30 through the different positions *b*, *c*, *d* and *e*, the point of contact of the weight 8 with the threads of the beam advances along the curved surface 17 to the positions 22, 23, 24 and 25 successively, and the angle formed 35 by the radial line 18, 18 with the lines 26, 27, 28 and 29 increases in obliquity as the weight 8 descends. As the radial line 18, 18 represents the direction in which the force of gravity acts on the weight 8, the effective pressure of the weight upon the threads of the beam will decrease as the weight descends and thereby compensate for the increase in force required to rotate the beam by the withdrawal of its threads at a 40 constantly decreasing diameter of the beam. 45

Weights 30 are adjustably held upon the arms 9 by a clamping screw 31. By the adjustment of the weights 30 and also by raising the axes of the arms 9, the initial effective pressure of the weights 8 may be adjusted as desired, thereby enabling the operator to regulate with great nicety the tension upon the individual threads as they are withdrawn from the beam. By the delicate adjustment and uniformity of tension upon the threads delivered from the warp beam I am enabled to produce a twisted cord of uniform tensile strength and more uniform in size and twist.

I claim,

1. In a tension device, the combination with a thread beam, of a weight arranged to rest upon the threads held on said beam and carried upon the free ends of arms pivotally held upon a horizontal rod supported in adjustable bearings, and means for vertically adjusting said bearings, consisting of adjusting screws having swiveled connections with said bearings.

2. In a tension device, the combination with a thread beam, of a weight arranged to rest upon the threads held on said beam, perpendicularly above the axis of said beam, with the under side of said weight convexly curved to present substantially uniform areas of contact perpendicularly above said axis and tangential to the cylindrical surface of the threads held upon the beam, as the diameter of the beam is decreased by the withdrawal of threads therefrom, said weight being carried upon the free ends of arms pivotally held at one side of the thread beam, means for vertically adjusting the pivotal support of said arms, and adjustable weights carried on said arms.

GEORGE L. BROWNELL.
